BOTTLE CRATE

John F. Maurer, Jr., North Bergen, N. J.

Application May 17, 1933, Serial No. 671,478

5 Claims. (Cl. 217—19)

This invention relates to bottle crates or cases of the type that are usually used for milk bottles and the invention has to do with an improved means for bracing the bottom of the crate structure so that it will more effectually withstand the severe strains and stresses to which it is subjected.

Primarily the invention comprehends a brace strap, preferably constructed of sheet metal, which is constructed in such a manner as to afford abutments which engage with the opposite sides of the usual longitudinally extending bottom bars so as to maintain the same in their normal position and to resist side strains and thrusts imparted thereto, in addition to so tying the bottom of the crate structure together as to materially strengthen the same.

As a further object the invention includes, in combination with a brace strap of the indicated character, a reenforcing cleat anchored to the inner faces of the crate sides adjacent the lower edges thereof and with which cleats, abutments on said strap engage so as to assist the cleats in strengthening the bottom portions of the sides to withstand the impact of the shocks and jars especially when hand trucks are thrust thereagainst in handling the crates.

The invention also resides in the provision of upturned extremities at the opposite ends of the brace strap which straddle the sides of the crate and through which extremities, the bottom bars and the crate sides, tie rods extend to effectively lock the bottom structure more firmly together.

The invention furthermore contemplates the use of means extending through the brace strap and anchored in the bottom bars for securing the strap against the under surfaces of said bars so that the strap abutments are maintained in engagement with the opposite sides of said bottom bars.

Other objects of the invention are to provide a bottom bracing means which is not complicated in its construction and which may be inexpensively incorporated in the crate structure and which is highly efficient for its intended purpose.

With these and other objects in view reference is made to the following specification and the accompanying drawing in which there are set forth several preferred embodiments of the invention while the claims set forth the actual scope thereof.

In the drawing:—

Figure 1 is a fragmentary transverse sectional

view through a crate structure made up in accordance with the invention.

Figure 2 is a fragmentary longitudinal sectional view on a larger scale taken approximately on the line indicated at 2—2 in Figure 1.

Figure 3 is a fragmentary perspective view of one end of the brace strap.

Figure 4 is a fragmentary transverse sectional view illustrating a slightly modified form of the invention.

Referring to the drawing by characters of reference A designates the sides of the crate, B the bottom bars, which are transversely spaced with reference to each other and the crate sides and which extend longitudinally of the crate.

The bottom bracing means constituting the present invention includes a brace member which is preferably in the form of a sheet metal strap 5 which is of a length to extend completely across and to underlie the bottom of the crate and which is provided with upturned extremities 6 at its opposite ends, which extremities are apertured as at 7 to receive therethrough a combined tie rod and partition element 8 which extends through the crate sides and the bottom bars B, the tie rod having upset ends or heads 9 thus more firmly locking together the bottom structure.

The body portion of the strap or member 5 is provided with abutments 10 which engage with the opposite sides of the bottom bars B so as to maintain the same in their normal position and resist side strains and thrusts imparted thereto while tying the bottom of the crate structure together to brace and counter brace the same. The brace strap or member 5 is provided with additional abutments 11 adjacent to and spaced from the terminals 6 for either directly or indirectly engaging the crate sides A.

In the form of the invention illustrated the bracing means includes in combination with the brace member or strap 5, brace cleats 12 which are secured to the inner faces of the sides A adjacent the lower edges thereof and with which the abutments 11 engage.

In order to maintain the abutments 10 in relative position on opposite sides of the bottom bars B, fastening means such as screws 13 or their equivalent extend through the strap or member 5 and are anchored in the bottom bars. The abutments 10 and 11 may be variously formed but preferably they are made integral with the strap or member 5 and as shown in Figures 1 to 3 inclusive are produced by slitting and bending up tongues from the body of said strap or mem-

ber so that the end edges are disposed in contact with the elements which they abut.

In the form of the invention illustrated in Figure 4, the abutment tongue 15 has a terminal portion 16 extending upwardly at an angle to afford a wider bearing surface or area to engage or contact with the element which it abuts. In other respects the use or purpose as well as the structure of the bracing means is identical with that set forth in connection with the preferred form of the invention.

From the foregoing it will be seen that a crate bracing means has been devised which although of simple construction and capable of economical incorporation in the crate structure, materially adds to the length of life and usefulness of the crate by strengthening the same at the point where it is subjected to the greatest strains. While there has been shown and described several preferred forms of the invention, it is to be understood that other variations which fall within the range of the claims may be resorted to when desired.

What is claimed is:—

25 1. In a bottle crate which includes sides and transversely spaced, longitudinally extending cross sectionally rectangular bottom bars having bottle receiving depressions opening through the upper wall and opposite side walls thereof, means

30 for bracing the bottom portion of the crate structure including reinforcing cleats attached to the inner faces of the crate sides and a transverse brace strap secured at its opposite ends to the crate sides and having abutment means engaging 35 the inner side faces of the cleats and the opposite side faces of the bottom bars adjacent the bottom faces thereof.

40 2. A transverse bottom brace for a bottle crate of the type which includes longitudinally extending cross sectionally rectangular bottom bars having bottle receiving depressions opening through the upper wall and opposite side walls thereof spaced from each other and from the crate sides, said bottom brace being formed from 45 a length of strap material having upturned opposite terminals anchored to the crate sides and a body portion having spaced pairs of upwardly offset abutments disposed substantially in planes parallel to the plane of the strap body with the 50 free end edges of the abutments of each pair engaging opposite side faces of the bottom bars.

3. A transverse bottom brace for a bottle crate of the type which includes longitudinally extending cross sectionally rectangular bottom bars having bottle receiving depressions opening through the upper wall and opposite side walls thereof spaced from each other and from the 55 crate sides, said bottom brace being formed from a length of strap material having upturned opposite terminals anchored to the crate sides and a body portion having upwardly offset abutments alternately extending in opposite directions with the free end edges of the outermost abutments in engagement with the inner faces of the crate sides and with the free end edges of the remaining abutments engaging the opposite side faces of the 60 bottom bars.

4. In a bottle crate having sides and longitudinally extending cross sectionally rectangular bottom bars having bottle receiving depressions opening through the upper wall and opposite side walls thereof disposed in spaced parallel relation to each other and to the crate sides, means for bracing the bottom of the crate including cleats secured to the inner faces of the crate sides adjacent the lower edges thereof, a transverse brace 100 strap underlying and extending across the entire crate, upturned terminals at the opposite ends of the brace strap, a combined partition and tie rod extending through the upturned terminals, the 105 crate sides and the bottom bars, means anchoring the strap to the bottom bars and upwardly offset abutments on the brace strap extending alternately in opposite directions and disposed in planes substantially parallel to the plane of the 110 strap with the free end edges thereof engaging respectively with the inner side faces of the cleats and the opposite side faces of the bottom bars adjacent the bottom faces thereof.

5. A transverse bottom brace for a bottle crate of the type which includes longitudinally extending bottom bars having opposite side faces formed with bottle receiving depressions, said bottom brace being formed from a length of strap material having its opposite ends supported by the 115 crate sides and spaced offset abutments disposed substantially in a plane parallel to the plane of the strap with the free end edges of the abutments engaging opposite upright side faces 120 of said bottom bars beyond the confines of the 125 bottle receiving depressions.
